UNITED STATES PATENT OFFICE

JAMES A. STRUTHERS, OF MINNEAPOLIS, MINNESOTA

DESIGN FOR A STOCKING

Application filed May 12, 1930. Serial No. 35,598. Term of patent 14 years.

To all whom it may concern:

Be it known that I, JAMES A. STRUTHERS, a citizen of the United States, residing at Minneapolis, in the county of Hennepin and State of Minnesota, have invented a new, original, and ornamental Design for a Stocking, of which the following is a specification, reference being had to the accompanying drawings, forming part thereof, wherein:

Fig. 1 is a view in side elevation of a stocking, showing my new design;

Fig. 2 is a view in rear elevation of the same.

The important features of my design comprise the parallel upwardly extending tongues which merge into the enlarged base portions, said tongues being defined by straight parallel lines and having outwardly and oppositely extending lateral projections also defined by straight lines adjacent the upper ends of the tongues.

What I claim is:

The ornamental design for a stocking, substantially as shown.

JAMES A. STRUTHERS.
